(57) CLAIM

The ornamental design for a sports brassiere, as shown and described.

DESCRIPTION

FIG. 1 is a front perspective view of a sports brassiere in accordance with the present invention;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a front perspective view of the sports brassiere in an inside-out configuration in accordance with the present invention;

FIG. 10 is a rear perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and,

FIG. 16 is a right side elevation view thereof.

The broken lines in the drawings depict portions of the sports brassiere that form no part of the claimed design.
